UNITED STATES PATENT OFFICE.

ALEXANDER S. DECARIE, OF MONTREAL, QUEBEC, CANADA.

INCINERATOR CONSTRUCTION.

Application filed May 12, 1922. Serial No. 560,439.

To all whom it may concern:

Be it known that I, ALEXANDER S. DECARIE, a subject of the King of Great Britain, and resident of the city of Montreal, in the 5 Province of Quebec and Dominion of Canada, have invented certain new and useful Improvements in Incinerator Constructions, of which the following is a full, clear, and exact description.

10 This invention relates to improvements in incinerators, and the primary object of the invention is to provide means for establishing a positive circulation of water through the grates which support garbage 15 during incineration. A further object is to provide a grate or the like having a continuous water passage therethrough, including the entire grate. Another object is to provide a grate so constructed that the circulation of water will be automatically induced by the different temperatures prevailing in different parts of the grate. Still another object is to provide a grate constructed to so distribute the water circulating therethrough that a clearly defined circulation is induced owing to the relative speeds at which water is heated at different parts of the grate. A subsidiary object is to provide one efficient form of water cooled 20 grate.

It has already been proposed to provide water cooled garbage grates in an incinerator, but it has been found in practice that the cooling is not efficient because the circulation is defective, with the result that parts, or sometimes the whole grate, become dry owing to steam pocketing and excluding water.

The present invention deals with the construction of rotatably mounted hanging or suspended incinerator grates, which are provided to hold the garbage to facilitate its destruction. The grates are adapted to discharge the material thereon by the hinging or rotating movement about their support. In my invention, the grates are constructed in such a manner that a circulation of water will be positively maintained through all parts of the grate at all times. In other words the invention deals broadly with the provision of an efficient circulation and continuous circulation of water through the grate.

The establishment of water circulation

may be effected in different ways. Preferably 55 the grate is so constructed that the water will circulate naturally. The essential feature is that the grate must constitute a continuous passage for the water without pockets. One method of accomplishing this is 60 disclosed in the following detailed description and annexed drawing of a depending incinerator grate, and embodies the main supporting member of tubular construction, which may serve as the outlet. The frame 65 and bars of the grate are all of tubular construction, the frame serving as an inlet and the bars as communication between the inlet and outlet. This arrangement is preferred in the from shown, for the reason that the 70 comparatively large frame members are located at the margin of the grate where the heat is relatively low, and furthermore because these frame members will carry a larger volume of water than the bars with the 75 result that the incoming water will be heated less quickly in the frane than in the bars, thus establishing a natural circulation.

It will be understood, however, that the invention is not limited in any particular 80 to the precise construction shown and described, as this is purely by way of explanation, but that the invention embraces any construction of incinerator grate adapted for a positive circulation of water through 85 all parts thereof.

In the drawings:

Fig. 1 illustrates one embodiment of the invention and shows a longitudinal view of a garbage support partly in section. 90

Figure 2 is a view showing the incinerator in side elevation with one of the walls removed.

Figure 3, is a sectional elevation of a portion of the grate. 95

Referring more particularly to the drawings, 11 designates opposite walls of an incinerating chamber, above which is mounted a water and steam drum 12, and between which there is provided a swinging garbage 100 support designated as a whole by the numeral 13.

A large and strong tubular member 14 extends through both walls 11, and is provided at each end with a stuffing box 15. 105 A water inflow pipe 16 is connected in any suitable way to the lower part of the drum 12, and passes through one of the stuffing

boxes 15 into the tubular support 14. Within the support 14 there is arranged a pipe 17, connected at one end to the pipe 16 by any suitable sort of connection designated 5 18, which will permit of the pipes 16 and 17 being independently and relatively rotated. Branch pipes 19 are provided leading from the pipe 17 and passing through the wall of the support 14 adjacent the inner 10 cinerator walls 11, or otherwise as may be desired. These pipes 19 generally speaking, depend from the support 14, but it will be understood that their exact position and relation to the vertical is immaterial to 15 the present invention. The lower ends of the branch pipes 19 are connected to one another by a pipe 20, which is generally speaking horizontal and parallel with the support 14, but which may be otherwise disposed if desired. The members 14, 19 and 20 constitute the main frame of a garbage support. A plurality of pipes 21 of any suitable size and spacing are connected between the pipes 14 and 20, and afford 25 communication between these pipes. The combined flow capacities of the pipes 21 are preferably approximately equal to the flow capacity of the pipe 17. The elbows or fittings designated 22, which serve to connect 30 the pipes 19 and 20, are of much heavier, and more rigid construction than is usual, and in addition form a casing of considerable length designated 23, around the pipes 19, so as to afford a rigid joint between the 35 pipes 19 and 20 and also to relieve the threads of the pipes 19 where they screw into these fittings of mechanical stress. The main support 14, where it passes through the walls 11, is encased in sleeves 24, each of 40 which is provided with a radial extension 25, embracing a pipe 19, so as to form a loose connection between this pipe and the pipe 14. The sleeves 24 run in bearings 26 carried by the walls 11, and these bearings 45 may for convenience and ease of operation, be of the roller type illustrated. The sleeves 24 are provided outside the walls with extension arms 24^a. To oscillate the grates, power is transmitted through the arms 24^a, from 50 a source not shown to the sleeve 24 and the radial extensions 25 to the pipes 19 and 20 which form the main frame of the garbage support or grate. The radial arms are made to embrace a considerable length 55 of the pipes 19 to relieve said pipes and the joints from excessive strain due to the turning movement. The end of the support 14 remote from the pipe 16 is provided with a tubular outlet 27, passing through the stuffing box and connected to any suitable 60 point of the drum 12. The inlet 16 and outlet 27 are disposed concentric with the pipe 14 or with the outer surface of the sleeves 26, if these outer surfaces are not 65 parallel with the pipe surface. A water

supply pipe may be connected in any suitable way, for example leading in through the pipe 27, as indicated at 28.

The operation of the device is as follows: The apparatus being filled with water to a suitable level and heat applied, a circulation of water is set up in a well-known manner. The colder portion of water in the drum 12 flows through the connection 16 and pipe 17 to the pipes 19 and 20, and thence through the pipes 21 into the pipe 14 and back to the drum through the pipes 27 and 29. This circulation establishes itself owing to the fact that the inflowing cold water travels in comparatively large volume through the comparatively cool marginal frame members 19 to the pipe 20. The water then flows in comparatively small columns through the pipes 21, which are more highly heated, so that the water heats quickly in these pipes and escapes to the tubular support 14. The circulation is much enhanced owing to the grate being so positioned in use that the pipe 14 is above the pipe 20, so that the cold water flows down to the lower ends of the pipes 21, and on being heated rises through the pipes 21. Owing to the fact that the combined flow capacities of the pipes 21 are about equal to the flow capacity of the inlet, all the pipes 21 will be filled with water so that none can run dry. It will be understood, however, that the circulation may be otherwise arranged, especially if the construction of the grate differs from the construction herein disclosed. The water in the pipes 14, 19 and 20 and 21, also the water in the drum, is heated from the burning garbage. The garbage is supported on the grid or grate formed by the pipes 19, 20 and 21 which have been swung to co-operative relation with some other element, such as another similar support or a side wall of the incinerator. The air passes freely through the supporting grid, so that the combustion is facilitated and promoted. If it is desired to move the grate for the purpose of dumping garbage or ash therefrom, this may be effected by applying rotative force to either or both of the sleeves 24, through the arm 24^a. The said sleeves transmit motion directly to the pipes 19, thus relieving the joints between these pipes and the main support 14 of any stress which would produce leakage. The swinging grate may be held in any position by the application of holding force to one or both of the sleeves 24, and as these sleeves project through the furnace walls 11, it will be understood that the grate moving or holding means is thus protected from injury by the fire.

Having thus described my invention, what I claim is—

1. A device of the character described comprising a tubular support, inlet and out-

- let pipes at opposite ends of said support, a rectangular tubular grate frame having one side member thereof lying within said support and connected to the inlet pipe, the 5 opposite side member of the frame being disposed in spaced parallelism with said support, and a series of tubes connected between the support and the last mentioned side member of the grate frame.
- 10 2. A device of the class described, comprising a tubular support, stuffing boxes at opposite ends thereof, an inflow and an outflow pipe passing through said stuffing boxes at opposite ends of the support, a pipe disposed within the support and connected to said inflow pipe, lateral branches from said last mentioned pipe passing through the wall of the support, a tubular connection between the free ends of said lateral pipes, a 15 plurality of tubular connections between the first mentioned tubular connection and the tubular support, and rotating means for said support, said means being in embracing engagement with said branches to impart movement directly thereto.
- 20 3. In combination with a device according to claim 2 a connection between the inflow pipe and the extension pipe permitting relative rotation of the pipes, and means rigidly 25
- holding the said inflow and outflow pipes, 30 whereby the same constitute pivots about which the supporting pipe may rotate, and means secured to the tubular support to impart movement to the same.
4. A device of the class described, comprising tubular supports, grate sections depending from said supports and positioned within a combustion chamber, said sections comprising straight end pipes, cross pipes connecting the free ends of said straight 40 pipes and intermediate pipes attached to the tubular supports at their upper ends and to the cross pipes at their lower ends, said intermediate pipes being curved or bent at their 45 lower ends, said tubular supports having internal construction which taken in conjunction with the grate sections presents a continuous passage for the circulation of a cooling agent from the tubular support, 50 through the grate sections and back into the tubular support, means adapted to oscillate the grate about its suspension means, and means to transmit the power required to oscillate the grate sections. 55

In witness whereof, I have hereunto set my hand.

ALEXANDER S. DECARIE.
